UNITED STATES PATENT OFFICE.

JOHN N. LINDQUIST, OF MARQUETTE, MICHIGAN.

NECK-YOKE CENTER.

1,375,920.

Specification of Letters Patent. Patented Apr. 26, 1921.

Application filed April 13, 1920. Serial No. 373,491.

To all whom it may concern:

Be it known that I, JOHN N. LINDQUIST, a citizen of the United States, residing at Marquette, in the county of Marquette and State of Michigan, have invented certain new and useful Improvements in Neck-Yoke Centers, of which the following is a specification.

This invention relates to improvements in neck yoke centers and the method of securing them in position upon the yokes, and has for its particular object to provide such a device which can be manufactured and sold to farmers and blacksmiths in a shape 10 that can be applied to different diameters of roughly constructed yokes, such as is usually found in country districts.

Another object is to provide a center which can be easily secured to the yoke in a substantial manner without the use of 20 holding bolts or screws, and which will not become loose on the yoke from either constant use or shrinking of the yoke material.

A still further object of the invention is 25 to provide a certain specifically-shaped tool to be used in applying the center to the yoke, so that a farmer or unskilled mechanic, can with this tool and a hammer securely attach the center in place.

These and other objects are attained by 30 the means illustrated in the accompanying drawing, in which:—

Figure 1 is a side elevation of a neck yoke with the center in position, and also a single 35 attaching wedge in position, shown in full lines, to secure the center in place.

Fig. 2 is a transverse section on the line 2—2 of Fig. 1.

Fig. 3 is a detail longitudinal section, 40 taken on the line 3—3 of Fig. 1.

Fig. 4 is a detail perspective view of the attaching wedge, and

Fig. 5 is a transverse section through the 45 center alone showing approximately its shape before its assembly on the yoke.

Figs. 6 and 7 are detail views showing modified forms of wedges.

Similar reference numerals in all of the figures of the drawing designate like parts.

The yoke 5 is hewn, turned or otherwise 50 shaped preferably with an enlarged center portion and tapering ends. The yoke center is preferably formed of malleable iron or soft steel, and comprises a collar 6 which is 55 curved to semi-circular form and has secured to each pair of opposite corners a

semi-circular metal loop 7 made from suitable material, preferably of circular cross-section. The loops have their ends attached to the plate in any suitable manner, such as 60 brazing or welding, or by rivets passing through the flattened ends 8 thereof, as shown clearly in Fig. 1 of the drawing, but preferably the loops and plate are drop-forged. The loops are thus spaced apart 65 the longitudinal distance between the corners of the plate and extend transversely of the yoke between opposite corners, and loosely secured in any suitable manner through the loops 7 is a pole-ring 10, which 70 is formed with a straight bar 11 that extends longitudinally of the yoke from one loop 7 to the other, and a semi-circular loop 12 which connects with the bar 11 on the outside of the transverse loop 7. A pole- 75 ring of the shape thus described and shown in the drawing has a slight upward movement in the loops 7, and only a slight side swing which is caused by the vehicle contacting with an obstruction, thus avoiding 80 a wide side swing which is transmitted to the neck harness and causes the necks of the animals to become chafed and sore from the constant rubbing of the harness.

Collar 6 is formed with slight inturned 85 edges 13 which preferably only extend a portion of the plate and serve to indent into the yoke material, and the ends of these in-turned edges form shoulders 14 which prevent rotary movement of the center on the 90 yokes. Longitudinal inturned edges 15 can also be formed on the lower edges of the collar 6 if desired, which can be used together with the circular inturned edges 13 or alone.

As thus formed, it is intended that the 95 centers be manufactured in quantities by suitable manufacturers and distributed to the trade in the country districts, so that a farmer or blacksmith can secure them and fit them to yokes of their own make. As 100 made and sold by the manufacturers, the centers are preferably wide and open, as shown in Fig. 5 of the drawing, so that they can be slipped upon yoke arms of rough 105 construction and of various diameters.

The method of securing these centers to the yoke arms is an important feature of this invention, and said method is described as follows: The unskilled mechanic heats 110 the center to a brown red and then slips it in position upon the yoke arm. The brown

red heat is not sufficient to burn the wood, but makes the metal material of the center slightly bendable, so that it will conform to the shape of the exterior of the yoke arms 5 when pressure is applied. After the center has been slipped upon the yoke arm, a particularly formed wedge 20 is inserted through the loops 7 and against the underside of the yoke arms and driven home.

10 The pressure of the wedge bends the collar around the yoke arm into tight engagement therewith and buries the slightly inturned edges of the collar in the wood, then after this part of the operation, the center is preferably struck a sharp blow with any suitable tool at points near the rivet 8 on each side to bend the intermediate portion of the center farther inwardly below the yoke arm. After the metal of the center cools, the 20 wedge is withdrawn.

Wedge 20 is preferably formed of iron or tool-steel and is provided with a longitudinal groove 21 which is adapted to engage over the bar 11 and move thereon when it is being driven to wedging position, thus guiding it in a straight line, and is also provided with a notch in its driving end to form a shoulder 22 to be used in withdrawing it from wedging position. This avoids 30 using the front end for releasing the wedge.

When only one wedge is used, as shown in Fig. 1, it is withdrawn before the metal of the center entirely cools, and is then driven through the other side, and while this 35 method of using only one wedge is sufficient for all general purposes, to secure better results, preferably two wedges are used, as shown in Fig. 6. Where two wedges are used they can be short with squared ends, as shown 40 at 18 in Fig. 7 which would make them exactly alike, or the ends could be inclined as shown at 19 in Fig. 6 so that they would slide one upon the other. A plate 23 can be used on the underside of the yoke-arm to

prevent wear by the wedges when the center 45 is being placed, or by the pole-ring when the yoke-arm is being used.

Having thus fully described the invention, what is claimed is:—

1. In a neck-yoke, a center embodying a 50 collar partially surrounding the yoke arm and embedded therein throughout its area by pressure, transverse loops connecting opposite corners of said collar, and a pole-ring suspended from said transverse loops and 55 provided with a straight bar extending from one loop to the other.

2. In a neck-yoke, a center embodying a collar partially surrounding the yoke arm and embedded therein throughout its area 60 by pressure and provided with continuous slightly inturned end edges adapted to be pressed into the material of said yoke arm, transverse loops connecting opposite corners of said collar, and a pole-ring suspended 65 from said transverse loops and provided with a straight bar extending from one loop to the other.

3. In a neck-yoke, a center embodying a collar partially surrounding the yoke arm 70 and embedded therein throughout its area by pressure and provided with continuous slightly inturned end edges and intermediate longitudinal edges adapted to be pressed into the material of said yoke arm, transverse 75 loops connecting opposite corners of said collar, and a pole-ring suspended from said transverse loops and provided with a straight bar extending from one loop to the other.

4. A neck-yoke having a center embodying a collar-plate supported in a depression in the yoke arm, said depression being formed by forcibly bending the collar with sufficient pressure into engagement with the yoke arm to cause the collar to compress 85 the material forming the yoke arm.

In testimony whereof I affix my signature.
JOHN N. LINDQUIST.
